US0D1026372S

(12) **United States Design Patent** (10) **Patent No.:** **US D1,026,372 S**
(45) **Date of Patent:** **** May 7, 2024**

(54) **BUCKET LINER**

(71) Applicant: **DONGGUAN YINGDONG TECHNOLOGY CO., LTD,**
Guangdong (CN)

(72) Inventor: **Hailun Sha**, Guangdong (CN)

(**) Term: **15 Years**

(21) Appl. No.: **29/885,541**

(22) Filed: **Feb. 25, 2023**

(51) **LOC (14) Cl.** **07-05**

(52) **U.S. Cl.**
USPC **D32/53**

(58) **Field of Classification Search**
